UNITED STATES PATENT OFFICE.

CHARLES W. KECKLER, OF NEWARK, NEW JERSEY, ASSIGNOR TO WESTERN ELECTRIC COMPANY, INCORPORATED, OF NEW YORK, N. Y., A CORPORATION OF NEW YORK.

AUTOMATIC TELEPHONE SYSTEM.

1,367,705.

Specification of Letters Patent.

Patented Feb. 8, 1921.

Application filed March 21, 1917. Serial No. 156,314.

To all whom it may concern:

Be it known that I, CHARLES W. KECKLER, a citizen of the United States, residing at Newark in the county of Essex and State 5 of New Jersey, have invented certain new and useful Improvements in Automatic Telephone Systems, of which the following is a full, clear, concise, and exact description.

10 This invention relates to substation circuits for use with substation sending devices for automatic telephone exchange systems.

Heretofore in automatic telephone systems in which the calling subscriber operates a calling device or impulse sending mechanism to control the operation of selecting apparatus, it has been necessary that the subscriber remove his receiver from the switchhook before operating his calling device, so as to allow a line finder or an equivalent switch to operate at the central office to extend the line circuit to the selecting apparatus which is to be controlled by the first series of impulses.

25 The object of this invention is the provision of a substation circuit arrangement for use with a calling device whereby the line circuit is closed to start the line finder or an equivalent switch at the central office 30 as soon as the calling device is moved from its normal position. An off-normal contact is closed by the initial movement of the dial of the calling device which completes a bridge across the line conductors and allows 35 the line finder to operate before the impulses are transmitted by the return movement of dial to its normal position.

This invention may be more readily understood by reference to the accompanying 40 drawings, in which Figure 1 shows a preferred substation arrangement embodying this invention; and Fig. 2 shows a modification of the circuit arrangement shown in Fig. 1.

45 Referring to Fig. 1 of the drawings, 1 designates the usual ringer in series with a condenser 2 in the normal circuit of the line conductors 3 and 4. A telephone transmitter 5 and a primary winding 7 of an induction coil 6 are included in a normally open bridge of the line conductors, and are arranged to be brought into circuit upon the removal of the telephone receiver 9 from its switchhook 10. The receiver 9 and the secondary coil 8 of the induction coil 6 are also

arranged to be brought into circuit upon the removal of the receiver.

Associated with the substation circuit is a calling device 11 having a dial 12 rotatable about the axis 13 and provided with the teeth 14. A bellcrank lever 15, pivoted at 16 is located in operative relation to the dial 12. One arm of the lever is engaged by the teeth of the dial 12, and the other arm is engaged by the contact arm 17, which also engages the contact 18. The contact arm 17 is connected to contact 24 by a conductor 26. Two conductors, 19 and 20, extend from the induction coil leads, as shown, and terminate in the contact 21 and the contact arm 22 respectively. An arm 23 is fastened to the wheel 12 and is removable therewith. Contacts 24, 21 and contact arm 22 constitute an off-normal switch, and the closing of this switch when the calling device moves from normal places a bridge across the line conductors 3 and 4, and also places a shunt around the receiver 9, which shunt is maintained until after the required number of impulses is sent and the calling device returns to normal.

The operation is as follows, it being assumed that the calling party does not remove his receiver until after he has started operating his calling device to send out the first set of impulses. Only so much of a telephone system has been shown as is thought necessary for a complete understanding of the invention. The system herein disclosed is similar to that shown in Patent No. 1,281,013, issued June 26, 1917, to C. L. Goodrum. As a preliminary to the sending of the impulses, the dial 12 is moved in the direction of the arrow a required distance corresponding to the number of impulses to be sent, after which it is returned to normal by the action of a spring (not shown). As soon as the dial leaves its normal position, a circuit is closed for the start magnet 30 of the line finder from grounded battery, right-hand winding of relay 30, line conductor 4, conductor 27, contact 18, contact arm 17, conductor 26, contact 24, conductor 19, primary coil 7, line conductor 3, left-hand winding of relay 30 to ground. Relay 30 becomes energized and starts the line switch operating to extend the line conductors 3 and 4 to a first selector. As soon as the calling line is found cut-off relay 41 is energized and opens the circuit of relay 30.

In the return of the dial 12 to its normal position, the teeth 14 engage the bell-crank lever 15, thereby making and breaking, at contacts 17 and 18, the bridge across the line circuit which by this time extends to the first selector and completes a circuit for a line relay 40 of this selector. The relay 40 is thereby energized and deenergized a number of times corresponding to the number of impulses transmitted, to move the selector to the desired group of trunks. The relay 30 will be deenergized at this time, because as soon as the line finder finds the calling line the cut-off relay 41 is energized to open the circuit of relay 30.

The moving of the dial from normal also places a short circuit, conductor 19, contacts 21 and 22 and conductor 20, about the receiver. The switch contact 22 is arranged to engage contact 21 before the circuit through contact 24 is completed. When this circuit is completed through the primary coil 7 to start the line finder, and later made and broken to transmit impulses to the selector switch, the current which is induced in the secondary by these current changes does not affect the receiver because of the shunt around it. Therefore, when the subscriber removes his receiver during the operation of the calling device, he does not receive a disagreeable click in his receiver each time a circuit change is produced.

Upon the dial reaching its normal position, arm 23 engages contact arm 22, thereby opening the shunt for the circuit of receiver 9, but there is no effect produced in the receiver, since at this time there is a steady flow of current through the primary coil from ground at the selector, conductor 3, contact arm 10, transmitter 5, contact arm 17, contact 18, conductor 27, line conductor 4 to grounded battery at the selector.

In Fig. 2, the switch contact 22 is connected directly to the line conductor 3 and is provided with only the off-normal contact 24. It is not believed that a complete description of the operation is necessary, as it is similar to that above described, except that the circuit for energizing relay 30 and the signaling circuit do not extend through the primary coil 7 of the induction coil as in Fig. 1, as the calling device in this circuit arrangement short-circuits all of the substation apparatus as soon as it leaves its normal position. The disadvantage of this

circuit arrangement shown in Fig. 2 is that the calling subscriber receives a click in his receiver at the end of each dial movement, when current is reestablished through the primary of the induction coil.

60

What is claimed is:

1. In a substation circuit for an automatic telephone system, a calling device having normally closed impulse springs, a normally open line circuit, a hook switch, a normally open short-circuit around the hook switch, and means operated by the initial movement of said calling device for closing said short-circuit and closing said line circuit through said impulse springs.

65

2. In a substation circuit for an automatic exchange system, a calling device having impulse springs, sets of off-normal springs controlled by said calling device, a line circuit including said impulse springs and one set of said off-normal springs, and a short circuit around the telephone receiver controlled by another set of said off-normal springs.

70

3. In a substation circuit for automatic telephone systems, a calling device having normally closed impulse springs, a normally open line circuit, a receiver, a normally open short circuit around said receiver, and means operated by the initial movement of said calling device for first closing said short circuit and then closing said line circuit through said impulse springs.

75

4. In a substation circuit for automatic telephone systems, a calling device having impulse springs and sets of off-normal springs, a line circuit including said impulse springs and one set of off-normal springs, a telephone receiver, and a short circuit around said receiver including another set of off-normal springs.

80

5. In a substation circuit for automatic telephone systems, a calling device having impulse springs and sets of off-normal springs, a line circuit including said impulse springs and one set of off-normal springs, a telephone receiver, a short circuit around said receiver including another set of off-normal springs, and means controlled by the movement of the calling device for closing the short circuit in advance of closing the line circuit.

85

In witness whereof, I hereunto subscribe my name this 20th day of March A. D., 1917.

CHARLES W. KECKLER.
